PAINT CAN OPENER

Frank A. Trimboli, 137 Mechanic St., Red Bank, N.J.

Filed Jan. 29, 1965, Ser. No. 83,630

Term of patent 7 years

(Cl. D54—13)

FIG. 1 is a side elevation of a paint can opener embodying the new design.

FIG. 2 is an elevation of the opposite side of the paint can opener.

FIG. 3 is an inside or underneath view of the opener looking at the left hand side of FIG. 1.

FIG. 4 is an outside view of the device, looking toward the right hand side of FIG. 1.

FIG. 5 is a top plan view of the device looking down on FIG. 1.

FIG. 6 is a bottom plan view looking upward on FIG. 1.

I claim:

The ornamental design for a paint can opener, substantially as shown.
